CLAIM

The ornamental design for a cervical plate, as shown and described.

DESCRIPTION

FIG. 1 is a top perspective view of a cervical plate showing our new design;

FIG. 2 is a top plan view thereof;

FIG. 3 is a right side elevation thereof, the side opposite being a mirror image;

FIG. 4 is an end elevation thereof, the end opposite being a mirror image; and,

FIG. 5 is a bottom plan view thereof.

The broken lines showing environmental structure are for illustrative purposes only and form no part of the claimed design.
